UNITED STATES PATENT OFFICE

ESTLE H. SHAW, OF JOHNSON CITY, NEW YORK, ASSIGNOR TO ENDICOTT JOHNSON CORPORATION, OF ENDICOTT, NEW YORK, A CORPORATION OF NEW YORK

SHOE LINING

Application filed August 18, 1930. Serial No. 476,161.

This invention relates to shoes and has particular reference to the manner of making the lining for the rear quarters of the shoe and the method of attaching the same to the quarters. To facilitate an understanding of the invention I will explain it with reference to the accompanying drawing which illustrate the lining and the method of attaching the parts thereof together and to the quarter of the shoe, to enable others skilled in the art to adopt and use the same, and concisely state the invention which I desire to protect in the claims following such explanation.

15 In said drawing:

Fig. 1 is a perspective view of the rear quarters of a shoe upper, with my improved lining attached thereto.

Fig. 2 is a front view of the lining detached.

Fig. 3 is a detail view illustrating the first step in attaching the lining to the quarter.

Fig. 4 is an enlarged detail section on the line 4—4 Fig. 1.

25 While the invention can be used in shoes of various types it is particularly designed for low shoes, and in the drawing the lining is shown suitable for the quarter of so called "Blucher" shoes for men or "Oxford" shoes for women. The quarters Q of the shoe form no part of the present invention and may be made of leather or any other suitable material, and as shown the opposite quarters are connected together at the back 30 of the shoe by a seam indicated at S; and these quarters may be ornamented if desired.

The lining consists of seven pieces; including a central heel engaging member 4 and right and left members 2, 1, 3. The right and left members 2 are attached to opposite sides of the member 4 respectively preferably by stitching. The right and left members 1 are attached to the outer edges of the right and left members 2 respectively as by stitching. The right and left members 3 are attached to the upper edges of the right and left members 1 and 2 respectively. The members 3 and 4 are preferably made out of soft durable material preferably leather such as kid; the members 2 may be made of stiffer leather

or other suitable material; and members 1 are preferably made of canvas. The member 4 extends above the members 2 when attached thereto, the extension thereof forming a projecting reinforcement tab or stay 55 4a projecting above the top edge of the lining.

The seven pieces of the lining are cut according to patterns in substantially the forms shown in Fig. 2, and when united form 60 a lining substantially conforming in shape to the form of the quarters. The upper edges of such lining are stitched to the upper edges of the quarters as indicated at S3 65 in the drawing.

After the members of the lining have been properly cut to pattern, the members 1 and 2 are attached together by stitching as indicated at 2s. The members 3 are then respectively attached to the adjacent upper or 70 front edges of the members 1 and 2 by stitching as indicated at 3s. Then the two parts (each comprising members 1, 2 and 3) are attached to opposite sides of the heel member 4 by stitching indicated at 4s, the wrong side 75 of the stitch appearing on the rear face of the lining.

After the members of the lining have been stitched together as described the inner face of the lining is placed against the outer face 80 of the quarters (see Fig. 3) and the tab 4a is stitched to the center or heel portion of the quarters adjacent the upper edge thereof, while the lining and quarters are face to face as at S2. Then the lining is turned over 85 the upper edge of the quarters and against the inner face thereof so as to bring the inside face of the lining and the inside face of the quarters together. This results in folding the tab 4a over the seam S2 and over the upper edge of the quarters, as shown in Fig. 4. Then the upper edges of the lining and quarters are stitched together as at S3 starting 90 at the forepart of the quarter. When the stitcher reaches the reinforcement tab or stay, the cutting knife is thrown out, then the shoe is stitched across the reinforcement tab, then the knife is again thrown in and the stitching continued on to the forepart on 95 the other side of the quarter.

When assembled in the shoe the forward edges of the quarters and lining are connected to the rear edges of the upper of the shoe in the usual manner, this forming no part of the present invention. The eyelets of the shoe are usually formed in members 3.

15 The operator who stitches the lining and the quarters together usually locates the position where the reenforcing tab or flap is to be stitched by pin pricks in the leather of the quarters.

16 It will be seen that in this construction the heel member 4 protects the heel of the wearer from contact with the seam between the quarters, and the tab 4a being attached to the quarters by stitching as described and then folded over and again stitched to the quarters as shown forms a very strong bond uniting the upper edges of the quarters together at the back seam, and also prevents the heel member breaking down or the seam between the quarters rupturing, and the heel member provides a smooth surface for contact with the ball of the heel of the wearer 20 insuring greater comfort.

25 I claim:—

1. In a shoe; a quarter lining comprising a central heel member of soft material and adjacent members of stiffer material stitched together; the heel member having a tab on its upper end blind stitched and over-seamed to the upper edge of the quarter on the exterior thereof; the upper edges of adjacent members of the lining being stitched to the 30 upper edge of the quarter.

2. In a shoe; a quarter lining comprising a central heel member of soft material and adjacent side members of stiffer material, stitched together; the heel member having a tab on its upper end blind stitched and over-seamed to the back of the quarter near the upper edge on the exterior thereof; the upper edges of the adjacent portions of the lining being stitched to the upper edge of the 40 quarter.

3. In a shoe; a quarter lining comprising a central heel member of soft material, adjacent members of stiffer material, outer members of fabric, and eyelet members of leather; 45 said members being stitched together; the heel member having a tab on its upper end blind stitched and over-seamed to the back of the quarter near the upper edge thereof on the exterior thereof; the upper edges of the other members of the lining being stitched to the upper edge of the quarter.

ESTLE H. SHAW.
